UNITED STATES PATENT OFFICE.

JULIAN ZAKRZEWSKI AND JOHN KARASINSKI, OF DETROIT, MICHIGAN.

ELECTRIC SNAP-SWITCH.

1,154,473.

Specification of Letters Patent. Patented Sept. 21, 1915.

Application filed April 26, 1915. Serial No. 24,621.

To all whom it may concern:

Be it known that we, JULIAN ZAKRZEWSKI and JOHN KARASINSKI, subjects of the Czar of Russia, residing at Detroit, in the county 5 of Wayne and State of Michigan, have invented certain new and useful Improvements in Electric Snap-Switches, of which the following is a specification.

This invention relates to certain new and 10 useful improvements in electric snap switches.

The primary object of the invention is to provide an electrical switch of the form generally known as a snap switch and which is 15 provided with but a single reciprocating actuating member, the successive opening and closing of the switch being accomplished by succeeding pushing impulses imparted to the actuating member.

20 A further object of the invention is to provide normally separated switch contacts with a closing means operable upon alternate manual actuations of a push button device, the intermediate impulses of the push button serving to release the contacts for automatically returning to their normal separated open positions.

With these general objects in view and others that will appear as the nature of the 30 invention is better understood, the same consists in the novel combination and arrangement of parts hereinafter more fully described, illustrated in the accompanying drawings, and pointed out in the appended claim.

In the drawings forming a part of this application and in which like-designating characters refer to corresponding parts throughout the several views:—Figure 1 is a 40 longitudinal sectional view taken through the switch casing, parts being broken away. Fig. 2 is a top plan view of the device with the front plate of the casing removed. Fig. 3 is a transverse sectional view taken upon line III—III of Fig. 1. Fig. 4 is a sectional view taken upon line IV—IV of Fig. 2. Fig. 5 is an enlarged perspective view of the 45 engaging pawl. Fig. 6 is an enlarged perspective view of the pinion plate, and Fig. 7 is an enlarged perspective view of the operating rack.

Referring more in detail to the drawings, it will be seen that a casing 10 is provided 55 formed of any desired insulating material having a front plate 11 with a slot 12 there-

through, while the upper edge of the casing is provided with oppositely arranged slots 13.

Two spring contacts 14 and 15 are positioned within the slots 13 and are provided with binding screws 16 for retaining the line 60 wires 17 in engagement with the contacts. The said contacts 14 and 15 extending obliquely within the casing 10, have angular portions 18 engaging the casing bottom 19 and secured thereto by means of screws 20. 65 The terminal ends of the contact springs 14 and 15 are upwardly curved as at 21 and 22 respectively forming resilient contact arms normally spaced apart as best illustrated in Fig. 1 and positioned in overlapping engagement and in contact with each other upon forcibly depressing the contact arm 22.

A frame is mounted within the casing upon the bottom 19 thereof by means of a 75 base plate 23 secured thereto by screws 24 and having opposite trunnion posts 25 between the upper ends of which a shaft 26 is secured. A star wheel 27 is journaled upon the shaft 26 and is arranged for engaging the free ends 28 of its arms with the contact arm 22 upon a revolution of the wheel, thus effecting electrical connection between the arms 21 and 22. The hub 29 of the star wheel has a ratchet wheel 30 secured to its inner end, it being understood that the star wheel hub and ratchet wheel are both journaled upon the said shaft 26. 85

A pinion plate 31 is journaled upon the said shaft 26 by means of a perforation 32 90 through the said plate, the latter being provided with an extended hub 33 through which the said shaft freely extends. A torsion coil spring 34 encircles the pinion plate hub 33 and has one end 35 secured to the 95 adjacent post 25, while its other end is secured as at 36 to the pinion plate, whereby the force of the spring normally retains the pinion plate in a tilted position as illustrated in Fig. 1, with the heel 37 of the base portion 38 of the plate normally resting upon the frame base 23. The pinion plate base portion 38 has a U-shaped pawl 39 of the form illustrated in Fig. 5 pivotally mounted thereto by means of a pin 40 and 100 normally held engaging the notched side portion 41 of the pinion plate by means of a curved looped wire spring 42 engaging the pawl notches 43 and having its central portion seated within the pinion plate notch 110

44. This arrangement of the pawl positions the engaging tooth 45 upon the side thereof adjacent the ratchet wheel in constant engagement with the ratchet wheel 30.
- 5 A spring dog 46 is secured to the frame base plate 23 and has its free end in constant ratcheting engagement with the said wheel 30 for permitting the ratchet wheel to revolve in but a single direction.
- 10 An operating rack 47 of the form best illustrated in Fig. 7 is rectangular in longitudinal cross section and has side flanges 48 positioned in sliding engagement between side guides 49, while the inner face 50 of
- 15 the rack is provided with a plurality of perforations 51 forming intervening portions 52 corresponding to teeth, the teeth 53 of the pinion plate being constantly positioned in engagement with some of the rack perforations 51.
- 20 The rack 47 normally projects through the casing plate slot 12 as shown in Fig. 1 and has a push button 54 secured to the top thereof. In operating the device, an inward impulse exerted upon the push button 54 by the finger of the operator forces the rack 47 inwardly, thus tilting the pinion plate 31 upon the shaft 26 and the pawl tooth 45 being brought into engagement
- 25 with one of the teeth of the ratchet wheel 30, the star wheel 27 is thereby revolved bringing the engaging end 28 of one of the arms thereof into engagement with the contact arm 22 for depressing the same against
- 30 the contact arm 21, the relative change of positions of the contact arm and star wheel being from the position shown in Fig. 1 to that of Fig. 4. Upon such a positioning of the star wheel as just described, the
- 35 spring 46 will engage one of the teeth of the ratchet wheel 30 retaining the star wheel so positioned, while a release of the push button 54 allows the spring 34 to revolve the pinion plate and automatically return
- 40 both the plate and its rack 47 to their normal position. A succeeding similar actuation of the push button rack and pinion
- 45

plate will result in turning the star wheel a one-eighth turn which will release its engaging arm 27 from the contact arm 22, 50 allowing the contact arms to automatically separate, it being understood that the spring 46 then engages a succeeding tooth of the ratchet wheel.

A readily operable snap switch is thus 55 provided in which each alternate actuation thereof makes and breaks the electrical connections between the terminal contacts of the switch.

While the form of the invention herein 60 shown and described is what is believed to be the preferred embodiment thereof, it is nevertheless to be understood that minor changes may be made without departing from the spirit and scope of the invention 65 as claimed.

What is claimed as new is:—

A snap switch comprising a casing, a frame mounted therein, a shaft journaled in the frame, normally separated terminal contacts between the said shaft and frame, a star wheel journaled upon the said shaft and having its arms provided with a path of movement in the plane of the said contacts, a ratchet wheel connected to the said star wheel, a pinion plate journaled upon the said shaft, an engaging pawl for the said ratchet wheel pivoted to the said plate, the said pawl being U-shaped and having 70 opposite notches therein, and the said pinion plate being provided with a notch in its base portion, a looped curved wire spring 75 having a central portion secured within the said pinion plate notch and with its free ends engaging the said pawl notches and 80 a shiftable actuating rack for the said pinion plate.

In testimony whereof we affix our signatures.

JULIAN ZAKRZEWSKI.
JOHN KARASINSKI.
